WATER SAMPLING DEVICE

Blair H. Stone, Pekin, Ill., assignor to Dearborn Chemical Company, Chicago, Ill., a corporation of Illinois

Application May 11, 1942, Serial No. 442,478

5 Claims. (Cl. 73—21)

This invention relates to improvements in water sampling devices and it consists of the matters hereinafter described and more particularly pointed out in the appended claims.

It is common practice to take samples of locomotive boiler water so that it may be analyzed to determine the various constituents thereof and the proper treatment to be administered thereto to make it more suitable for use. Heretofore, the usual custom was to take a piece of rubber tubing and place it upon a short stub pipe which is associated with a valve on the water glass and gage cock of the locomotive. The other end of the hose was placed in the mouth of a container, such as a glass bottle of convenient size, and the valve opened so that boiler water flowed into the container. There are several objections to this practice. First, the stub pipe referred to is located usually in a very confined and awkward position, making it difficult to attach the rubber tubing. Second, the boiler water is very hot and there is considerable steam discharged with the water. Due to the position of the parts mentioned and the necessity of the operator to hold the hose in one hand and the container in the other hand, there is danger of hot water and steam scalding the operator taking the sample.

One of the objects of the present invention is to provide a simple, inexpensive and efficient device by which a water sample may be taken from a locomotive boiler with safety to the operator avoiding the danger of being scalded by hot water or steam.

Another object of the invention is to provide a device of this kind which may be conveniently held in one hand of the operator, thus leaving the other hand free for such duties as may be required at this time.

Again, it is an object of the invention to provide a device of this kind from which steam may readily escape before the steam and hot water enter the container, thus eliminating breaking of the container due to an accumulation of pressure therein.

Also, it is an object of the invention to provide a water sampling device of this kind which contains no valves, springs or other parts requiring adjustments and service so that the device is capable of continued use over a long period of time.

The above mentioned objects of the invention, as well as others together with the several advantages thereof will more fully appear as the specification proceeds.

In the drawing:

Fig. 1 is a vertical sectional view through a water sampling device embodying the preferred form of the invention.

Fig. 2 is a horizontal sectional view through the device as taken on the line 2—2 of Fig. 1.

Referring now in detail to that embodiment of the invention illustrated in the drawing, the improved device embodies therein an upright hollow body 5 preferably made of metal. It includes an upright cylindrical side wall 6, a domed top wall 7 and a bottom end tubular neck 8. Said neck, which is of smaller diameter than the body, is internally threaded to receive the complementary and externally threaded neck 9 of a receiver 10, which may take the form of an ordinary glass bottle. In the bottom of the body is a perforated plate 11, against which a rubber gasket 12, in the upper end of the neck engages. In turn said gasket is adapted to be engaged by the lip end of the neck 9 to provide a good tight connection between the body 5 and the container 10.

Opening through one side of the domed top wall 7 of the body is a nipple 13 having parts 13a and 13b disposed outside and inside of the body respectively, the axis of said nipple being inclined to the perpendicular axis of the body. A tubular open ended sleeve 14, of relatively fine mesh screen, is fixed at its upper end to the part 13b of the nipple and the lower open end of said sleeve is disposed to discharge substantially axially of the body 5 and neck 8.

A rubber tube 15 has a friction fit at its bottom end on the nipple part 13a and an angle nipple 16 is frictionally fitted in the upper end of said tube. While the tube 15 is flexible, it is still stiff enough to stand in its normal upwardly inclined condition without such bending as will cause the tube to kink or collapse. Thus while the axis of the upper end of the nipple 16 is disposed parallel with the axis of the body 5, it is spaced laterally from said axis and is located at a point considerably above the domed top of the body.

A plurality of holes 17 is formed in the upper portion of the side wall 6 of the body adjacent the nipple 13 and through which steam may escape from the interior of the body to atmosphere. On the opposite side of the body and midway between its top and bottom ends is an upright radial flange or rib 18 disposed in a slit or kerf in the inner end of a handle 19. Screws 20 pass through said inner end of the handle and said flange or rib to secure the handle to the body. Preferably the handle is made of poor heat conducting material, so that it remains cool enough at all times to be comfortably held in the hand.

When drawing a sample of water from a locomotive boiler, the device as a whole, with the container 10 connected thereto, is held in one hand by means of the handle 19. While thus held, the nipple 16 is caused to engage with the stub pipe associated with the gage glass valve of a locomotive boiler. Using the other hand, said valve is opened and steam and water under boiler pres-

sure flow into the nipple 16 and down the tube 15 and through the nipple 13 and sleeve 14 and into the body 5. While the sleeve is made of screen that presents a large number of openings, these are relatively small or fine and the water, being more or less solid, will be guided in the general direction of the length of the sleeve to be discharged into the bottom of the body to pass through the openings in the plate 11 and into the receiver bottle 10. In the passage of the water and steam down the sleeve 14, a part of the steam will pass through the openings therein to enter the top end of the body and there mingle with the steam that may arise from the bottom of the body. This steam will then escape through the openings 17 in the body to atmosphere. As the handle 19 is on that side of the device opposite the openings 17, it is apparent that the steam escaping therefrom cannot engage the hand grasping the handle. Thus, from the foregoing it is apparent that the entire device including the container or bottle 10 is held by one hand and this in a manner so that the hand cannot be scalded.

It is also apparent that as water enters the receiver, the air therein is displaced upwardly to enter the body through the holes in the plate 11 and then passes out through the openings 17 with the escaping steam.

When the required water sample has been deposited in the bottle, the valve before mentioned is closed and the device withdrawn from the stub pipe. The container or bottle 10 is then unscrewed from the neck and a cap is applied to the bottle so that it may be transmitted to the laboratory for test purposes.

It is to be noted that the device comprises but a few parts which are not relatively movable and that there is a complete absence of small parts and springs so that the device cannot readily get out of order.

While in describing the invention I have referred in detail to the form and arrangement of the parts, the same is to be considered only in the illustrative sense so that I do not wish to be limited thereby except as may be specifically set forth in the appended claims.

I claim as my invention:

1. A portable boiler water sampling device embodying therein a hollow closed top body formed at the bottom to provide an outlet neck that is adapted to have a boiler water sample receiver detachably connected thereto, means providing a boiler water inlet member that opens through an upper portion of said body, a conduit made of such material as to be self-supporting yet capable of some flexing, attached at one end to said water inlet member, the other end of said conduit being adapted for detachable operative engagement with a valve controlled water outlet of the boiler from which the water sample is to be taken, and means in the upper portion of the body for the escape of steam rising from the boiler water entering said body through said inlet member.

2. A portable boiler water sampling device embodying therein a hollow closed top body formed at the bottom to provide an outlet neck that is adapted to have a boiler water sample receiver detachably connected thereto, means providing a boiler water inlet member that opens through an upper portion of said body, a conduit made of such material as to be self-supporting yet ca-

pable of some flexing, attached at one end to said water inlet member and extending upwardly and outwardly therefrom toward its other end which is adapted for detachable operative engagement with a valve controlled water outlet of the boiler from which the water sample is to be taken, and means in the upper portion of the body for the escape of steam rising from the boiler water entering said body through said inlet member.

3. A portable boiler water sampling device embodying therein a hollow closed top body formed at its bottom end to provide an outlet neck that is adapted to have a boiler water sample receiver detachably connected thereto, means carried by the closed top of said body toward one side thereof of providing a boiler water inlet that opens into an upper portion of said body, a conduit made of such material as to be self-supporting yet capable of some flexing, attached at one end to said last mentioned means, the other end of said conduit being adapted for detachable operative engagement with a valve controlled water outlet of the boiler from which the water sample is to be taken, and means in said body below the top thereof for the escape of steam rising from the boiler water entering said body through said means carried by the top of said body.

4. A portable boiler water sampling device embodying therein a hollow closed top body formed at the bottom to provide a downwardly opening outlet neck, a boiler water receiver formed at one end for detachable supporting connection with said outlet neck to receive water therefrom and which receiver is made of material of such transparency that the level of the water sample therein may be ascertained therethrough, means providing a boiler water inlet member that opens through an upper portion of said body, a conduit made of such material as to be self-supporting yet capable of some flexing, attached at one end to said means providing said inlet member, the other end of said conduit being adapted for detachable operative engagement with a valve controlled water outlet of the boiler from which the water sample is to be taken, and means in the upper portion of said body for the escape of steam rising from the boiler water entering the body through said inlet member.

5. A portable boiler water sampling device embodying therein a hollow closed top body formed at the bottom to provide an outlet neck that is adapted to have a boiler water sample receiver detachably connected thereto, means providing a boiler water inlet member that opens through the closed top of the body and has parts arranged within and without said body, a tubular screen of relatively fine mesh fixed to said part of said inlet member within the body and extending downwardly therefrom toward said outlet neck, a conduit made of such material as to be self-supporting yet capable of some flexing, operatively connected at one end to said part of said inlet member outside said body, the other end of said conduit being adapted for detachable operative engagement with a valve controlled water outlet of the boiler, from which the water sample is to be taken, and means in the upper portion of the body for the escape of steam rising from the water entering said body through said tubular screen.

BLAIR H. STONE.
